(57) **CLAIM**

The ornamental design for an electrical outlet receptacle, as shown and described.

DESCRIPTION

FIG. 1 is a plan view of the electrical outlet receptacle shown within an environmental wall plate in accordance with a first

embodiment of the design, all of the alternative embodiments described below are dimensionally the same or similar to the embodiment of FIG. 1, the scale of FIG. 1 being smaller to accommodate the unclaimed environmental wall plate; FIG. 2 is an isometric view of the ornamental design shown in FIG. 1;

FIG. 3 is a plan view of the electrical outlet receptacle in accordance with an alternate second embodiment of the design;

FIG. 4 is an isometric view of the ornamental design shown in FIG. 3;

FIG. 5 is a plan view of the electrical outlet receptacle in accordance with an alternate third embodiment of the design; FIG. 6 is an isometric view of the ornamental design shown in FIG. 5;

FIG. 7 is a plan view of the electrical outlet receptacle in accordance with an alternate fourth embodiment of the design;

FIG. 8 is an isometric view of the ornamental design shown in FIG. 7;

FIG. 9 is a plan view of the electrical outlet receptacle in accordance with an alternate fifth embodiment of the design; FIG. 10 is an isometric view of the ornamental design shown in FIG. 9;

FIG. 11 is a plan view of the electrical outlet receptacle in accordance with an alternate sixth embodiment of the design; FIG. 12 is an isometric view of the ornamental design shown in FIG. 11.

FIG. 13 is a plan view of the electrical outlet receptacle in accordance with an alternate seventh embodiment of the design; and,

FIG. 14 is an isometric view of the ornamental design shown in FIG. 13.

The broken lines shown in the drawings represent portions of the electrical outlet receptacle that form no part of the claimed design.
